[57] **CLAIM**

The ornamental design for a electric can opener with vertical height adjustment, as shown and described.

DESCRIPTION

FIG. 1 is a top, front, left to the side perspective view of an electric can opener with vertical height adjustment showing my new design;

FIG. 2 is a front elevational view thereof;

FIG. 3 is a right side elevational view thereof;

FIG. 4 is a rear elevational view thereof;

FIG. 5 is a left side elevational view thereof;
FIG. 6 is a top plan view thereof;
FIG. 7 is a bottom plan view thereof;
FIG. 8 is a top, front, left side perspective view thereof shown in an alternate position;
FIG. 9 is a front elevational view of that shown in FIG. 8;
FIG. 10 is a right side elevational view of that shown in FIG. 8;
FIG. 11 is a rear elevational view of that shown in FIG. 8;
FIG. 12 is a left side elevational view of that shown in FIG. 8;
FIG. 13 is a top, front, left side perspective view of a second embodiment of that shown in FIG. 1;
FIG. 14 is a front elevational view of that shown in FIG. 13;
FIG. 15 is a right side elevational view of that shown in FIG. 13;
FIG. 16 is a rear elevational view of that shown in FIG. 13;
FIG. 17 is a left side elevational view of that shown in FIG. 13;
FIG. 18 is a top plan view of that shown in FIG. 13;
FIG. 19 is a bottom plan view of that shown in FIG. 13;
FIG. 20 is a top, front, left side perspective view of FIG. 13 shown in an alternate position;
FIG. 21 is a front elevational view of that shown in FIG. 20;
FIG. 22 is a right side elevational view of that shown in FIG. 20;
FIG. 23 is a rear elevational view of that shown in FIG. 20; and
FIG. 24 is a left side elevational view of that shown in FIG. 20.
